DESIGN FOR A CABINET FOR A COMBINATION KITCHEN UNIT OR SIMILAR ARTICLE

Guyon L. C. Earle, Forest Hills, N. Y., assignor to Hugh S. Wertz, trustee of Earle Patents Trust

Application September 22, 1945, Serial No. 122,261

Term of patent 14 years

(Cl. D33—13)

To all whom it may concern:

Be it known that I, Guyon L. C. Earle, a citizen of the United States of America, residing at Forest Hills, in the county of Queens and State of New York, have invented a new, original, and ornamental design for a Cabinet for a Combination Kitchen Unit or Similar Article, of which the following is a specification, reference being made to the accompanying drawing, forming a part thereof, and in which the single figure shows in perspective a cabinet for a combination kitchen unit or similar article.

The characteristic features of the present design reside in the portions shown by means of full lines in the drawing.

I claim:

The ornamental design for a cabinet for a combination kitchen unit or similar article, substantially as shown and described.

G. L. C. EARLE.
